UNITED STATES PATENT OFFICE

WILLIAM L. BEAN, OF WEST HAVEN, CONNECTICUT

LOCOMOTIVE-SMOKE-BOX STRUCTURE

Application filed March 5, 1925. Serial No. 13,242.

This invention relates to locomotive smoke-box structures, having many features of novelty relating to the draft appliances, including the deflectors and the spark-netting and to their means of attachment to the smoke box.

The invention will be best understood by reference to the following description, when taken in connection with the accompanying drawings of one specific embodiment thereof, while its scope will be more particularly pointed out in the appended claims.

In the drawings:

Fig. 1 is a central, vertical, longitudinal, sectional view of a portion of the front end of a locomotive, including the cylinder saddle, the smoke-box supported thereon, and the draft appliances.

Figure 2 is a vertical transverse section taken on the line 2—2 of Figure 1.

Figures 3, 4, 5, 6, 7, 8, and 9 are sections taken on the corresponding section lines of Figure 2.

Figure 10 is a view of the inside of the smoke-box wall illustrating the supports for the parts mounted thereon.

Figure 11 is a section illustrating the parts mounted on the smoke-box wall and showing the same independently of their mounting.

Figure 12 is a top view illustrating the horizontal deflector plates.

Referring to the drawings, and to the embodiment of the invention, which is selected for exemplification, and having reference more particularly to Fig. 1, the locomotive has a cylinder saddle 20, which presents a support for the smoke-box 21, the latter in the present example being a casting, as distinguished from a structure built up of sheet metal and other fabricated shapes. The smoke-box presents an opening 27 for an exhaust pipe 28.

The deflector, which deflects the gases in a downward direction and compels them to flow first to the forward end of the smoke-box, and thence in an upward and rearward direction through the spark netting into the path of the exhaust steam toward the stack, will now be described, reference being

had at first to Fig. 11. The deflector comprises a rear portion designated generally by the numeral 52, and a lower portion designated generally by the numeral 53, each of which is composed of a plurality of sections or plates now to be described, reference being had to Fig. 2. The rear portion comprises upper left and right plates 54 and 54', lower left and right plates 55 and 55', an upper inspection plate 56, and a lower inspection plate 57. The plates 54 and 54' have overlapping marginal portions 58 and 59 (see Fig. 3), and herein the marginal portion 58 is offset to provide a recess 60, which receives the marginal portion 59, thus providing a joint which prevents sparks from passing through, even though the plates should become warped to quite an extent. Similarly, the plates 55 and 55' are provided with overlapping marginal portions 61 and 62 (see Fig. 4), the former presenting a recess 63 which receives the margin 62. The plates 54 and 55 have tongue and groove connection with each other, the plate 54 to this end having a thickened marginal portion 64, presenting a groove 65, which receives a marginal portion 66 of the plate 55. The plates 54' and 55' have similar tongue and groove connection with each other (see Fig. 6), the plates 54' to this end having a thickened portion 64' presenting a groove 65', which receives a marginal portion 66' of the plate 55'.

The plates 54 and 55 are joined to each other about a pipe, herein a superheater pipe 67, and the plates 54 and 54' are joined to each other about another pipe, herein a superheater pipe 67', and to prevent the leakage of gases at these joints, there are provided packings, one of which is illustrated in Fig. 8. It will be remembered that the plate 54 is provided with a thickened marginal portion 64, which presents a groove 65 utilized in joining the plates 54 and 55 together. This thickened portion and its groove are continued in a half circle about the pipe 67 (see Fig. 2), and there is provided a packing 68 of appropriate fire-resisting material, such as asbestos, which

is received in this groove and extends there-
beyond into engagement with the periphery
of the pipe (see Fig. 8). The plate 55 has
a similar thickened marginal portion 69
(see Fig. 2), having a groove 70 to receive
the packing 68 which is in the form of a
ring about the pipe. A like packing con-
struction is employed between the plates 54',
and 55' and the pipe 67.

10 The upper inspection plate 56 has a
marginal portion 71, which, as shown in
Fig. 11, is offset to provide a recess 72 for
corresponding marginal portions of the
adjacent plates 54 and 54', and the joint
15 thus presented prevents the passage of
sparks through the deflector, even though
the plates should become warped to quite
a considerable extent. Similarly, the larger
20 inspection plate 57 has a marginal portion
73, which as shown in Fig. 18 is offset to
provide a recess 74 which receives the
adjacent marginal portions of the plates
55 and 55'. A tongue and groove con-
25 nection is provided between the inspection
plate 57 and the plates 54 and 54' by contin-
uing the thickened portion 64 and 64' and
their grooves 65 and 65'. It should now be
evident, by reference to Fig. 11, that the
30 inspection plate 57 can be slid in an upward
direction into the described groove in a
slightly inclined position, and its lower edge
then swung rearwardly into place. It is
conveniently secured in place by a series of
35 fastening elements, one of which is illus-
trated in Fig. 9. In the present example,
this fastening element is a pin 75, which is
permanently secured to the plate 55 or 55', as
the case may be, as by having a reduced
40 portion 76 which extends through the plate,
and is riveted or headed over at 77. The
body of the pin extends through an open-
ing 78 provided in the offset marginal por-
tion 73 of the plate 57, and this body
45 portion, where it extends through the plate,
receives a washer 79 conveniently held in
place by a split locking key 80 in an elon-
gated slot 81 provided in the pin. Like
fastening elements are employed for the
50 upper inspection plate. The inspection
plates may be provided with appropriate
handles 82 and 83, respectively (see Fig.
2), and as the plates 55 and 55' are rather
large and heavy, they may be provided with
55 similar handles 84 and 84'.

The lower portion 53 of the deflector will
now be described, reference being had to
Fig. 11. Here, the deflector extends about
the exhaust and live steam pipes, and to en-
able the deflector to be fitted about these
60 pipes, it comprises two plates 85 and 86
shown in plan in Fig. 12. The rear plate
85 has its rear marginal portion received in
grooves 87 and 87' presented by thickened
marginal portions 88 and 88' formed on the
65 plates 55 and 55', respectively. At this

point, it may be mentioned that the corner
of the deflector (see Fig. 11) is preferably
rounded on both sides. This form prevents
eddy currents and improves the draft by
70 promoting a smoother flow of gases below, as
well as above the deflector. The rear plate
85 is conveniently put in place by being set
at first in an inclined position, represented
in dotted lines in Fig. 11, to enable it to
75 clear the live steam pipes. It is then low-
ered and swung into position with its rear
marginal portion in the groove. The plates
85 and 86 likewise have tongue and groove
connection with each other, the plate 85 to
80 this end having a thickened marginal por-
tion 89 provided with a groove 90, which
receives the margin of the plate 86. This
thickened marginal portion is extended part
way about the live steam pipes 38 (see Fig.
85 12), and is provided with a similar groove
91, while the plate 86 has a similar thickened
marginal portion 92, provided with a like
groove 93. Referring now to Fig. 2, these
89 grooves may, and are herein, provided with
appropriate packing collars 94, of fire-
resisting material such as asbestos, which
projects beyond the grooves and engages the
peripheral surfaces of the live steam pipes
38. The packing prevents leakage and also
95 prevents wear of the parts due to one rub-
bing against the other. Where the plates
85 and 86 are disposed about the exhaust
pipe 28, they present an opening 95, which
receives the exhaust pipe, and above this
100 opening is provided a usual exhaust nozzle
96, which is secured to the plates, as well
as to the exhaust pipe, by bolts 97. In this
way, the plates are securely united with each
other and with the exhaust pipe, the latter
105 therefore serving as a pedestal to support
the plates.

The remaining supports for the deflector
will now be described, reference being had
at first to Fig. 10. The several plates 54,
54', 55, 55', 56 and 57, which compose the
110 deflector rear portion when fitted together,
have a circular marginal portion, which has
tongue and groove connection with the cir-
cumferential wall of the smoke-box, as by
providing the latter with an integrally
115 formed projection 98 (see Fig. 10), which
presents a groove 99 in which said marginal
portion is received. This interengagement
of the deflector and the smoke-box enables
the several plates composing the deflector to
120 be put in place and securely held, without
the necessity of employing any fastening
elements such as bolts, or the like. This
is a matter of considerable practical impor-
125 tance in the maintenance of locomotives, be-
cause, where bolts are used, inasmuch as
they are exposed to the abrasive and cor-
rosive action of the products of combustion,
they become corroded rapidly, and when it
130 becomes necessary to remove the deflector

for the purpose of obtaining access to the flues and other parts, it usually becomes necessary to destroy the bolts by cutting them off. With the described construction, 5 the removal of the deflector plates can be accomplished in a small fraction of the time usually consumed in removing the deflector plates of all former constructions.

Referring now to Fig. 2, the several plates 10 which compose the rear portion of the deflector are put in place by first introducing the lower left-hand plate 55, then the lower right-hand plate 55', then the upper left-hand plate 54, then the upper right-hand plate 54', and finally the inspection plates 15 56 and 57, which, by the way, lock the others in place and serve as key plates for the deflector structure.

Referring again to Fig. 10, the rounded 20 lower portions of the plates 55 and 55' are supported by projections 100 and 100', formed as integral parts of the smoke-box casting. These projections are prolonged horizontally 25 to afford support for the rear lower deflector plate 85. Upward movement of the rear corners of the plate 85 is conveniently prevented by the provision of stops, herein lugs 101' formed as integral projections from the 30 circumferential wall of the smoke-box casting. The lower front plate 86 is conveniently supported by having its end received in grooves 102' presented by projections 103', herein formed as integral parts of the smoke-box casting. The plate 86 is simply pushed 35 horizontally into place, and is secured in place by the previously described bolts 97, which secure the exhaust nozzle to the exhaust pipe.

Herein the plate 86 has a depending marginal portion 104, to which a damper plate 40 105 is secured, as by bolts 106. The ends of the damper plate are conveniently supported by being received in grooves 108', herein formed in projections 109', formed as integral parts of the smoke-box casting. In 45 the present example, the projections 103' and 109' are connected to each other by projections 110', formed as integral parts of the smoke-box, and these projections prevent the 50 passage of sparks which might otherwise occur at these points. At the rear of the described deflector, there is another deflector comprising a plate 111 (see Fig. 1), whose ends are received in grooves 112' presented 55 by projections 113', herein formed as integral parts of the smoke-box casting. It should be understood, of course, that, as is usual in locomotive practice, the rear edge 60 of this plate is below the lowermost row of superheater flues. Forward of this deflector plate is an adjustable damper plate 114, having pintles or trunnions 115', received in bearings 116', herein formed as integral parts of the smoke-box casting. 65 Projections 123 on the forward portion of

plate 86 form a groove for the spark-netting.

Reference is here made to my Patents 1,625,784, 1,639,792, 1,647,335, issued April 26, 1927, August 23, 1927, and November 1, 1927, respectively, on applications divided 70 from this application, as originally filed. I also refer to my copending application Serial No. 99,417, divided from this application as originally filed.

I claim:

1. In a locomotive smoke-box structure, a smoke-box wall and a deflector extending transversely thereof, said wall and deflector having tongue and groove connection with each other, said deflector comprising a plurality of plates lying in the same general plane and having tongue and groove connection with each other, at least one of said plates having its edges engaging the edges 80 of adjacent plates and serving to hold the latter in assembled relation with said wall.

2. In a locomotive smoke-box structure, a

smoke-box wall and a deflector extending

transversely thereof, said wall and deflector

having tongue and groove connection with

each other, said deflector comprising a

plurality of plates lying in the same general

plane and having tongue and groove connec-

tion with each other, at least one of said

plates being a key plate and having an end

and two side edges engaging adjacent plates

to hold the same in assembled relation with

each other and with said wall, said key plate

being slidable in a direction away from the

plate engaged by said end edge to provide

for removal of the plates from each other

and from said wall.

3. In a locomotive smoke-box structure, a smoke-box wall and a deflector extending transversely thereof, said wall and deflector having tongue and groove connection with each other, said deflector comprising a plurality of plates lying in the same general plane and having tongue and groove connection with each other, at least one of said plates having its edges engaging the edges 105 of adjacent plates to support said plates in assembled relation to each other and said wall.

4. In a locomotive smoke-box structure, a

circumferential wall having an inwardly

extending projection following the curvature

of the wall and provided with an inwardly

opening groove, and a deflector extending

transversely of said wall and having a mar-

ginal portion received in said groove, said

deflector comprising a plurality of plates

lying in the same general plane, at least

one of which plates is provided with a

groove and at least one other of which plates

has a portion received in said groove for

holding said plates in assembled relation

with each other and with said wall.

5. In a locomotive smoke-box structure, a

plurality of deflector plates arranged at an angle to each other, and a curved deflector plate connecting said first mentioned angularly disposed plates, the adjacent edges of said first mentioned angularly disposed plates and the edges of said curved connecting plate being provided with grooved portions for sliding engagement with each other.

6. In a locomotive smoke-box structure a cylindrical wall having an inwardly radially extending rib following the curvature of the wall and provided with an inwardly opening groove, and a plurality of flat plates movable transversely of said wall into and out of said groove for assembly with and removal from said wall, said sections having interengaging edges for holding said sections in assembled relation with said wall and with each other to form a spark deflector extending across said box.

In testimony whereof, I have signed my name to this specification.

WILLIAM L. BEAN.
